UNITED STATES PATENT OFFICE.

GUSTAF A. CARLSON, OF CHICAGO, ILLINOIS, ASSIGNOR TO THE BOYE NEEDLE COMPANY, OF CHICAGO, ILLINOIS, A CORPORATION OF ILLINOIS.

EMBROIDERY HOOP.

Application filed March 5, 1923. Serial No. 622,867.

To all whom it may concern:

Be it known that I, GUSTAF A. CARLSON, a citizen of the United States, residing at Chicago, in the county of Cook and State of Illinois, have invented new and useful Improvements in Embroidery Hoops, of which the following is a specification.

This invention relates particularly to embroidery hoops wherein an adjustable outer hoop is employed in combination with an inner hoop, whereby the outer hoop may be clamped upon the inner hoop with the material to be embroidered stretched over the inner hoop and clamped between the two hoops.

The primary object is to provide an improved and simplified device of this character which can be cheaply manufactured, which is durable, and which is thoroughly adapted to its purpose.

The invention is illustrated in the accompanying drawing, in which—

Fig. 1 represents a plan view of the improved device; Fig. 2, an elevational view of the outer hoop; Fig. 3, fragmentary views of the end portions of the outer hoop; Fig. 4, a detailed sectional view taken as indicated at line 4 of Fig. 1; Fig. 5, a section taken as indicated at line 5 of Fig. 3; and Fig. 6, a section taken at line 6 of Fig. 3, but showing the cam device secured in operative position.

In the illustration given, A represents an inner hoop, which may be an endless wooden hoop; and B, an adjustable outer hoop constructed in accordance with the invention.

The hoop B is preferably formed of tin plate, or other sheet metal. A strip of suitable sheet metal, or other sheet material, has its edges curled outwardly and then towards each other, the strip being also curved into circular form. Thus the circular strip is provided at its edges with hollow beads 1. One end of the annular strip has secured within the hollow beads 1 comparatively stiff wire members 2. These wire members project from the end of the metal strip and are curved to correspond with the curvature of the ring. If desired, the wires may be secured within the sockets by spot-welding, as at 3, or any other suitable means of securing the wires within their sockets may be adopted. The projecting ends of the wires are

adapted to slide freely in the hollow beads 1 of the other extremity of the annular strip. One end of the strip is equipped with a short metal bar 4, which is disposed between the beads 1 and secured to the strip, as by spot-welding at the points 5. One end of the strip 4 is provided with an outturned cam-stud 4^a which is disposed substantially flush with the end of the strip.

The other end of the strip or annulus is equipped with a short metal bar 6, which is disposed between the hollow beads 1 and preferably secured by spot-welding, as at 7. The strip 6 is equipped at one end with a pivot-stud 6^a, which is substantially flush with the end of the metal strip which forms the annulus. Upon the pivot-stud 6^a is secured a metal disk 8 which is adapted to rotate freely on the pivot-stud 6^a. The disk 8 is a substantial metal disk which is provided with a cam slot 8^a with which the cam-stud 4^a is in permanent engagement. The parts may be assembled by entering the wire projections 2 in the hollow beads which form guides therefor, bringing the ends of the annulus approximately together, applying the cam-disk 8 to the stud 6^a and riveting it in position, care being taken to have the cam-stud 4^a entered in the cam-slot 8^a. The periphery of the cam-disk 8 may be suitably notched to enable the disk to be turned readily.

It is obvious that the construction described enables the ring B to be contracted upon the ring A. The construction is simple, cheap and thoroughly adapted to its purpose.

The foregoing detailed description has been given for clearness of understanding and no unnecessary limitations should be understood therefrom.

What I regard as new and desire to secure by Letters Patent, is:

1. A device of the character set forth comprising a split ring having its meeting ends provided with hollow beads, wires secured within said beads at one end and extending into the guides afforded by the beads at the other end, a pivot-stud secured to said ring between the beads at one end, a cam-stud secured to said ring between the beads at the other end, and a disk journaled on said pivot-stud and provided with a cam-slot engaging said cam-stud.

2. A device of the character set forth comprising a ring-form sheet metal member provided with lateral hollow beads, curved wire members secured within said beads at one end of the device and working in the guide afforded by the beads at the other end of the device, a bar secured to said first named member between said beads at one end of the

device and equipped with a pivot-stud, a bar secured to said first named member between the beads at the other end of the device and equipped with a cam-stud, and a cam-disk journaled on said pivot-stud and having a cam-slot engaging said cam-stud. ¹⁰

GUSTAF A. CARLSON.
